United States Patent Office.

ERASTUS S. CUMMINS, OF CLARENCE, IOWA.

Design No. 4,483, dated November 22, 1870.

DESIGN FOR A WELL-CASING.

The Schedule referred to in these Letters Patent and making part of the same.

To all whom it may concern:

Be it known that I, ERASTUS S. CUMMINS, of Clarence, in the county of Cedar and State of Iowa, have invented certain new and useful Design for Well-Casing; and I do hereby declare that the following is a full, clear, and exact description thereof, reference being had to the accompanying drawing, and to the letters of reference marked thereon, which forms a part of this specification.

The nature of my design is fully illustrated by the accompanying drawing; and

It consists in the peculiar construction of a metallic well-casing.

A represents a metallic cylinder of any desired dimensions, having a flat bottom and a conical top, B.

From the apex of the cone B rises a pipe, C, as

shown, the cone forming shoulders for supporting the dirt around the well.

The cylinder is provided with perforations at a suitable height above its bottom, for the passage of the water.

What I claim is—

The design for metallic well-casing, as shown and described.

In testimony that I claim the foregoing as my own, I affix my signature in presence of two witnesses.

E. S. CUMMINS.

Witnesses:

C. ALEXANDER,
GEO. E. WEAVER.
